MACHINE FOR CLEANING DENTURES OR THE LIKE

Paul P. Krolik, 55 E. Washington St., and Theodore H. Perlman, 25 E. Washington St., both of Chicago, Ill.
60602

Filed Aug. 21, 1967, Ser. No. 8,340

Term of patent 14 years

(Cl. D49—1)

FIG.1

FIG.2

FIG.3

FIG.4

FIG.5

FIG. 1 is a side-elevational view of a machine for cleaning dentures or the like showing our new design;

FIG. 2 is a front elevational view thereof;

FIG. 3 is an elevational view of the opposite side thereof;

FIG. 4 is a top plan view thereof; and

FIG. 5 is a bottom view thereof.

The dominant features of my design reside in the portions shown in full lines, the electric cord being shown broken away for convenience of illustration.

We claim:

The ornamental design for a machine for cleaning dentures or the like, substantially as shown and described.
